UNITED STATES PATENT OFFICE.

JOHN LEWIS MILTON, OF CLEVELAND, OHIO, ASSIGNOR TO THE TEAGLE COMPANY, OF CLEVELAND, OHIO, A CORPORATION OF OHIO.

ELECTRIC SWITCH.

1,405,537.

Specification of Letters Patent. Patented Feb. 7, 1922.

Application filed March 29, 1920. Serial No. 369,689.

To all whom it may concern:

Be it known that I, JOHN L. MILTON, a citizen of the United States, residing at Cleveland, in the county of Cuyahoga and State of Ohio, have invented certain new and useful Improvements in Electric Switches, of which the following is a specification, reference being had therein to the accompanying drawings.

- 10 This invention relates particularly to switches adapted to ground electric circuits, such, for example, as circuits of electric ignition systems used on automotive vehicles.
- 15 The principal objects of my invention comprise the provision of a circuit controlling electric switch which has its cooperating electrodes or contact points enclosed in a dirt and weather proof casing, which is simple in construction, which is durable and reliable in operation, and which is capable of production at relatively low cost.

20 The nature of the invention will be more fully pointed out in the description which follows in connection with the accompanying drawings illustrating a preferred embodiment of the invention.

In the drawings—

Fig. 1 is a plan view of the switch.

30 Fig. 2 is a section on the line II—II, Fig. 1.

Fig. 3 is a section on the line III—III, Fig. 1.

Fig. 4 is a plan view of one of the switch 35 casing members detached.

Fig. 5 is a section on the line V—V, Fig. 4.

Fig. 6 is a plan view of one of the insulating blocks or washers.

Referring in detail to the construction 40 illustrated, 1 is a metal cup-shaped casing member preferably made of sheet metal, 2 is a flexible diaphragm of non-conducting material such as leather, and 3 is an annular metal supporting member upon which the 45 casing members 1 and 2 are mounted. The flat bottom wall of the cup-shaped member is formed with an aperture 1^a and has a pair of diametrically opposed inwardly turned lugs 1^b, 1^c and a similar pair of diametrically 50 opposed outwardly turned lugs 1^c, 1^d. 4 is a rod-like electrode member which is fixedly secured in the aperture of the casing member 1. The electrode member 4 has its inner end formed with an enlargement or head 55 constituting the electrode proper and on the

stem of said member are arranged three insulating washers 5, 6 and 7, the washer 5 being arranged on the inside of the cup-shaped member 1 and being formed with diametrically opposed notches 5^a, 5^a which embrace 60 the inwardly turned lugs 1^b, 1^b. The washer 6 is circular and fits the aperture 1^a of the member 1. The washer 7 is similar to the washer 5 and has its diametrically opposed notches arranged to embrace the outwardly 65 turned lugs 1^c, 1^c.

Preferably, a fourth insulating washer 8 is arranged out-side the washer 7 and a metal washer 9 and a spring locking washer 10 are interposed between the washer 8 and a nut 11 which is mounted on the threaded outer end of the electrode member 4. It will be seen that when the nut 11 is screwed tight the bottom wall of the casing member 1 is tightly clamped between the washers 5 70 and 7 and the electrode 4 is rigidly secured to the said casing member 1.

The extreme outer end of the electrode 4 is preferably fitted with a pair of washers 12 and a clamp nut 13 so that the end of the 80 electrode serves as a binding post adapted to receive the end of a flexible conductor.

14 is a movable electrode mounted on the middle of the diaphragm 2. This electrode as shown comprises an outer head or button 85 part 14^a, a neck 14^b and an inner head 14^c formed by riveting over the inner end of the neck 14^b on the metallic cupped washer 15 arranged on the inner side of the diaphragm. 16 is a coiled spring surrounding the electrode 4 and the washer 5. This spring serves to electrically connect the electrode 14 to the casing 1 and also to normally hold the electrode 14 out of contact with the fixed electrode 4.

95 The top wall of the cup-shaped casing member 1 is formed with an outwardly turned flange 1^d and the peripheral part of the diaphragm 2 is clamped between this flange and the annular support 3. The support 3 has on its rear side a peripheral flange 3^a, the inner side of which is shaped to form an under-cut shoulder 3^b. In the production of the switch the casing member 1 has its flange 1^d formed with an annular or endless dished formation as indicated by dotted lines in Fig. 2 and by full lines in Fig. 5; then, in assembling the cup-shaped member 1, the diaphragm 2 and the support 3, pressure is applied to the dished flange 1^d of 110

the member 1 to flatten it as shown in Fig. 2 and thereby expand its periphery into tight contact with the under-cut wall of the flange 3^a, so that the cupped member 1 and 5 the support 3 are effectively secured together with the peripheral part of the diaphragm 2 tightly clamped between them.

The support 3 and the casing members 1 and 10 2 are formed with diametrically opposed holes to receive screws 17, 17 by which the switch is attached to a supporting metal plate or wall 18.

In assembling the switch mechanism the electrode 4 is secured in the manner described to the bottom wall of the casing 1, the spring 16 is placed in position, the diaphragm 2 with the electrode 14 secured thereto is disposed over the top of the cup-shaped casing member 1, and finally the 20 support 3 is placed in position and the parts inserted in a press and the dished flange 1^d of the casing member 1 is flattened to secure the parts together in the manner above described.

25 When the conductor of the electric circuit is connected to the binding post end of the electrode 4, the said circuit is normally unaffected by the switch; but by simply pressing the button 14^a of the electrode 14 the latter is brought into contact with the electrode 4 so that current can flow from the 30 flexible conductor through the electrode 4, electrode 14, washer 15, spring 16, casing 1 and support 3 to the metallic frame structure 18 which is equivalent to ground.

In electric ignition systems for internal combustion engines, provision is commonly made for thus grounding the ignition circuit to stop the engine and it will be seen 40 that my improved switch is especially well adapted for such service. However, it should be understood that the invention is not limited to this particular use nor to the particular forms of construction illustrated 45 in the drawings which are intended simply for purposes of explanation and illustration.

What I claim is:

1. In an electric switch, the combination 50 of a casing comprising a rigid metal cup-shaped section adapted to form part of an electric circuit and a flexible non-conducting

diaphragm arranged to close the open side of the cup-shaped section, an electrode mounted on and insulated from the said cup-shaped section, a second electrode mounted 55 on the diaphragm, means comprising a spring interposed between and serving to electrically connect the cup-shaped section and the electrode on the diaphragm, said spring being adapted to normally hold the electrodes apart and to yield when pressure is applied to the diaphragm and permit engagement of the electrodes.

2. In an electric switch, the combination 60 of a casing comprising a rigid metal cup-shaped section adapted to form part of an electric circuit and a flexible non-conducting diaphragm arranged to close the open side of the cup-shaped section, an electrode mounted on and insulated from the said cup-shaped 65 section, a second electrode mounted on the diaphragm, means comprising a coiled spring surrounding the first named electrode and interposed between and serving to electrically connect the cup-shaped casing section 70 and the electrode on the diaphragm, said spring being adapted to normally hold the electrodes apart and to yield when pressure is applied to the diaphragm and permit engagement of the electrodes.

3. In an electric switch, the combination 75 of a rigid annular supporting section, a metal cup-shaped section adapted to form a part of an electric circuit and having a peripheral flange secured to the support, a 80 flexible diaphragm of non-conducting material clamped between the annular support and the flange of the cup-shaped section so as to close the open side thereof, an electrode mounted on and insulated from the 85 said cup-shaped section, a second electrode mounted on the diaphragm, means comprising a spring interposed between and serving to electrically connect the cup-shaped section and the electrode on the diaphragm, said spring being adapted to normally hold the electrodes apart and to yield when pressure is applied to the diaphragm and permit engagement of the electrodes.

In testimony whereof, I affix my signature. 90

JOHN LEWIS MILTON.
